US00D649990S

(12) **United States Design Patent**
Corbell et al.

(10) **Patent No.:** US D649,990 S
(45) **Date of Patent:** ** Dec. 6, 2011

(54) **ACTUATOR**

(76) Inventors: **Michael Corbell**, Trinity Beach (AU);
Kymmie Corbell, Trinity Beach (AU)

(**) Term: **14 Years**

(21) Appl. No.: **29/374,246**

(22) Filed: **Jul. 18, 2011**

(30) **Foreign Application Priority Data**

Jul. 7, 2011 (AU) 201113054

(51) **LOC (9) Cl.** 15-09

(52) **U.S. Cl.** D15/143
